UNITED STATES PATENT OFFICE.

DAVID E. JACOBS, OF NEW YORK, N. Y.

DESIGN FOR A HAIRPIN.

Application filed March 25, 1925. Serial No. 12,877. Term of patent 3½ years.

To all whom it may concern:

Be it known that DAVID E. JACOBS, a citizen of the United States, and resident of the city of New York, in the county of Kings and State of New York, has invented a new, original, and ornamental Design for Hairpins, of which the following is a specification, reference being had to the accompanying drawing, forming part thereof, in which,

Fig. 1 is a plan view of a hairpin embodying my new design; and

Fig. 2 is a sectional view thereof.

I claim:

The ornamental design for a hairpin as shown.

Dated New York city, March 23rd, 1925.

DAVID E. JACOBS.
